UNITED STATES PATENT OFFICE.

BONNIE JONES, OF WYNONA, OKLAHOMA.

SAFETY DEVICE.

Application filed March 22, 1928. Serial No. 263,787.

The present invention relates to a safety device for use more particularly in hooking a well off of power.

At the present time, the means for hooking the well off consists of wooden blocks, which necessitates the use of both hands and frequently considerable difficulty is experienced in properly positioning the blocks, and as a result, serious injury is sustained by the operator hooking off the well.

It is therefore the principal aim of my invention to provide a device for hooking off wells, in a safe and positive manner, the safety device embodying my invention being simple in construction, inexpensive, strong and durable, and further well designed for the purpose intended.

Other objects of the invention will become apparent as the nature of the invention proceeds and when taken in connection with the accompanying drawing.

In the accompanying drawing, forming a part of this application and in which like numerals designate like parts throughout the several views:

Figure 1 is a longitudinal sectional view through the safety device embodying my invention, the movable tubular member being shown in a raised position.

Figure 2 is a cross sectional view, taken approximately on the line 2—2 of Figure 1.

In the drawing, wherein for the purpose of illustration is shown the preferred embodiment of my invention, the numeral 1 designates what is known as the knock-off post, which is formed with an enlarged through opening, in which is secured the cylindrical casting 2, the same being formed at its upper end with a flange 3, that engages with the top of the knock off post and securing bolts 4 extend through the flange and the knock off post, in the manner as clearly shown in Figure 1, whereby the cylinder 2 is secured in a stationary manner.

A pair of diametrically opposed locking dogs 5 are pivoted at their lower ends in suitable cut out portions 6 provided therefor in the inner face of the upper portion of the stationary cylinder 2, the pivots for these dogs being shown at 7.

Expansible coil springs 8 are associated with the upper free ends of the diametrically opposed dogs 5 and the adjacent portions of the respective cut-out portions 6 for normally urging the dogs 5 inwardly into the

bore of the cylinder 2 and the purpose of these locking dogs will be presently described.

Extending longitudinally through the stationary cylinder 2 and adapted for sliding and rotatable movement therein is the elongated tubular member 9, which is formed at its upper end with a laterally extending handle portion 10.

The pull rod 11 extends through the elongated tubular member 9, the upper end of this pull rod having the usual clamp or stirrup 12 secured on the same.

The tubular member 9 is formed at the intermediate portion thereof with diametrically opposed notches 13 in the outer face thereof for cooperation with the respective pivoted dogs 5, and as is shown clearly in Figure 1, these notches gradually increase in depth from the upper to the lower ends thereof.

In assembling the safety device, the cylinder 2 is initially secured in the knock off post 1, after which the pull cord 11 is inserted through the cylinder. The tubular member 9 is then slipped over the upper portion of the pull rod and the clamp or stirrup 12 is then secured on the upper portion of the pull rod.

When the tubular member 9 is in its lowermost position, the handle portion 10 formed on the upper end of the tubular member will engage with the flange 3, as is readily obvious from the construction disclosed in Figure 1.

When it is desired to hook the well off of power, the handle 10 is moved upwardly until the notches 13 are at the same level with the pivoted dogs and when the well is on its upstroke, the tubular member 9 is turned a quarter of a turn, and on the down stroke of the well, the tubular member 9 will be checked by the dogs 5 being in engagement with the notches 13. The rod line hook will now drop loose from the clamp or stirrup on the rod line, as well as all of the weight being taken off of the tower and resting on the knock off.

The provision of a safety device of this character will prevent serious injuries being sustained by the operator in hooking off a well, and furthermore, the device will, at all times be positive and efficient in carrying out the purpose for which it is designed.

While I have shown the preferred embodiment of my invention, it is to be understood

that minor changes in the size, shape, and arrangement of parts may be resorted to, without departing from the spirit of the invention and the scope of the appended claims.

5 Having thus described my invention, what I claim as new is:

1. In a safety device of the class described, a stationary cylinder, an elongated tubular member slidably and rotatably arranged in 10 the cylinder and through which a pull rod is adapted to extend, the upper end of the pull rod engaging the upper end of the tubular member, a handle on the upper end of the tubular member for actuating the same, and 15 complementary means between the cylinder and the tubular member for locking the latter in a raised position.

2. In a safety device of the class described, a stationary cylinder, an elongated tubular member slidably and rotatably arranged in 20 the cylinder and through which a pull rod is adapted to extend, the upper end of the pull rod engaging the upper end of the tubular member, a handle on the upper end of the tubular member for actuating the same, and 25 complementary means between the cylinder and the tubular member for locking the latter in a raised position, said means comprising a pair of diametrically opposed dogs arranged 30 in cut-out portions formed in the inner wall of the cylinder, said dogs being pivoted at their lower ends, the tubular member being formed with a pair of diametrically opposed

notches for cooperation with the respective dogs when the tubular member is in a pre- 35 determined position, and resilient means associated with the free ends of the dogs for normally urging the same into the bore of the cylinder.

3. A safety device of the class described 40 comprising a vertically disposed stationary cylinder for disposition in a knock off post, an elongated tubular member arranged for slid- 45 able and rotatable movement within the cylinder, and through which a pull rod extends, the upper end of the pull rod extending into the upper end of the tubular member, the inter- 50 mediate portion of the tubular member being formed in its outer face with a pair of dia- metrically opposed notches, a pair of spring 55 pressed locking pawls pivoted at their lower ends in the cut-out portion provided therefor in the inner face of the cylinder at diametri- 60 cally opposed points for engagement with the respective notches to hold the tubular mem- ber in a raised position when the notches are in alignment with the dogs, and a handle on the upper end of the tubular member for manually actuating the tubular member to disengage the tubular member from locking 65 engagement with the dogs, said handle engag- ing the upper end of the cylinder to limit the downward sliding movement of the tubu- lar member.

In testimony whereof I affix my signature.
BONNIE JONES.
